[57] **CLAIM**

The ornamental design for a combined animal food dish and water dispenser, as shown and described.

DESCRIPTION

FIG. 1 is a perspective view of an animal food dish and water dispenser showing our new design;

FIG. 2 is a top plan view of the dish and water dispenser of FIG. 1;

FIG. 3 is a front elevational view of the dish and water dispenser of FIG. 1, the rear is a mirror image of the front view shown;

FIG. 4 is a right end elevational view of the dish and water dispenser of FIGS. 1-3;

FIG. 5 is a left end elevational view of the dish and water dispenser of FIGS. 1-4;

FIG. 6 is a sectional view taken on line 6—6 of FIG. 2;

FIG. 7 is a sectional view taken on line 7—7 of FIG. 2; and

FIG. 8 is a sectional view taken on line 8—8 of FIG. 2.

The broken lines in FIG. 1 are for purposes of illustration only and form no part of the claimed design.
